UNITED STATES PATENT OFFICE

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

SAFETY DEVICE FOR BUTTONHOLE-SEWING MACHINES

Application filed February 14, 1928. Serial No. 254,202.

This invention relates to buttonhole sewing machines having automatic buttonhole sewing and cutting mechanisms, and has for an object the provision of simplified means under the selective control of the operator during the operation of the sewing mechanism for (1) preventing the operation of the buttonhole cutting mechanism at the end of a sewing period or (2) for stopping the sewing mechanism at any time during the buttonhole sewing period, at the same time preventing the operation of the buttonhole cutting mechanism.

To the attainment of the ends in view there are provided (1) a manually operated device for breaking the train of connections which operates the buttonhole cutting mechanism, and (2) a manually operated trip for the stop-motion device; the two manually operated devices being so connected that the device for breaking the buttonhole cutting train of connections may be operated without tripping the stop-motion device, while the manual operation of the stop-motion tripping device invariably operates to break the cutting train of connections.

In the accompanying drawings Fig. 1 is a side elevation of a buttonhole sewing machine embodying the invention. Fig. 2 is a bottom plan view and Fig. 3 a rear end elevation of the machine.

In the preferred embodiment of the invention illustrated, 1 represents the bed, 2 the standard, 3 the bracket-arm and 4 the head of a buttonhole sewing machine having substantially the same constructive features as are embodied in the straight-buttonhole sewing machine disclosed in the Allen Patent No. 743,213 of November 3, 1903. Such a machine has the usual stitch-forming mechanism including the needle 5 and shuttle 6 the period of operation of which is controlled by the usual stop-motion device including the tilting stop-motion lever 7 which is pivoted at 8 to the frame-bracket 9. The stop-motion lever 7 carries an upwardly spring-pressed plunger-pin 10 which, when the lever 7 is shifted to stopping position, Fig. 1, is first depressed by the cam 11 and then elevated by the spring 12 as the stop-notch 13 comes into

register with the plunger-pin. The stop-motion lever 7 has a rigid forwardly extending arm 14 from the free end of which depends a treadle-operated rod 15 having in its side a notch 16 adapted to receive the latch-lever 17.

The latch-lever 17 is fulcrumed at 18 to the under side of the bed 1 and carries an adjustable tripping point 19 which is engaged by the tripping point 20 on the usual feed-wheel 21 to stop the sewing mechanism at the end of a buttonhole sewing operation. The latch-lever 17 is also formed with a third arm 22 which extends outwardly beyond the edge of the bed 1 in position to be engaged by the lower end 23 of the manually operated stop-motion trip-lever 24 fulcrumed at 25 on the bracket 25' and carrying the finger-piece 26 by which the lever 24 is manually operated.

The buttonhole cutting mechanism comprises the vertically reciprocating knife 27 which is actuated by the cutter-bar 28 journaled in the head 4 and connected by the link 29 to the lever 30 fulcrumed at 31 to the arm 3 and biased by the spring 32 to raise the cutter-bar. The rear end of the lever 30 carries a screw-pin 33 which extends laterally through the vertical slot 34 in the link 35 pivoted at 36 to the front end of the lever 37. The lever 37 is fulcrumed at 38 to the standard 2 and is formed at its rear end with a slot 39 entered by the lateral stud 40 fixed to the stop-motion plunger-bar 10. Pivoted at 41 on the link 35 is the latch-lever 42 formed at its upper end with a shoulder 43 which is normally held by the spring 44 in its full line position, Fig. 1, in engagement with and below the pin 33, to couple the lever 37 to the lever 30. When in its full line position, the latch-lever 42 completes the train of actuating connections between the stop-motion plunger-bar 10 and the cutter-bar 28.

Manually operated means are provided for breaking this train of connections by a forward pull on the latch-lever 42 to dotted line position, Fig. 1, to prevent actuation of the cutter-bar by the stop-motion device. Pivoted at 45 on the latch-lever 42 is the manually operated pull-bar 46 the front end of which is formed with a finger-piece 47 and

the rear end of which is formed with a slot 48 entered by the screw-pin 49 carried by the lever 24. There is thus provided a lost-motion connection between the pull-bar 46 and the lever 24; the slot 48 being of such length that a forward pull upon the finger-piece 47 to break the train of cutter-actuating connections will not actuate the lever 24 to trip the stop-motion device. On the other hand, a forward pull on the finger-piece 26 to trip the stop-motion device before a sewing operation is completed, operates through the bar 46 to shift the latch-lever 42 and break the train of cutter-actuating connections.

15 Thus the operator has at his disposal two finger-pieces 47 and 26 constituting selectively controlled means operable during the sewing for (1) preventing the operation of the buttonhole cutting mechanism at the end of a sewing operation or (2) stopping the sewing mechanism at any time during the sewing period and at the same time preventing the operation of the buttonhole cutting mechanism. With this arrangement there is 25 no possibility of the cutter being damaged by an attempted operation of the same when the work-clamp is out of its proper button-hole cutting position which it assumes at the end of a sewing operation.

30 Having thus set forth the nature of the invention, what I claim herein is:—

1. A buttonhole sewing machine having, in combination, a frame including a bed and overhanging gooseneck stitch-forming mechanism, stop-motion mechanism including a stop-motion lever tiltable between running and stopping positions, a buttonhole cutter, a connecting device above said bed between the stop-motion mechanism and buttonhole cutter, a latch below said bed for detaining the stop-motion lever in running position, a manually operated lever having its lower end arranged to engage and trip said latch for release of the stop-motion lever, the upper 40 end of said manually operated lever having a lost-motion connection with said connecting device.

2. A buttonhole sewing machine having, in combination, stitch-forming mechanism, 50 stop-motion mechanism including a stop-motion lever spring-pressed to stopping position, a buttonhole cutter, a connecting device between the stop-motion mechanism and buttonhole cutter, a three-armed latch-lever having one of its arms arranged to detain the stop-motion lever in running position, a feed-wheel having a tripping point adapted to engage another arm of the three-armed 55 latch-lever to release the stop-motion lever, a manually operated lever having its lower end arranged to engage the third arm of the three-armed latch-lever, and a connection between the upper end of said manually operated lever and said cutter connecting device.

for shifting the latter to disconnected position.

3. A buttonhole sewing machine having, in combination, stitch-forming mechanism, stop-motion mechanism including a stop-motion lever tiltable between running and stopping positions, means for detaining the stop-motion lever in running position, a vertically movable stop-plunger carried by said stop-motion lever, a buttonhole cutter, a train of connections between the stop-plunger and buttonhole cutter for operating the latter, said train of connections including a latch-lever movable forwardly or toward the operator to break said train, a vertically disposed manually operated lever mounted in rear of said latch-lever, a push-rod connecting the upper end of said manually operated lever with said latch-lever, said push-rod having a lost-motion connection with one of said levers, whereby the latch-lever may be moved to disconnecting position by operation of the manually operated lever or may be moved to disconnecting position independently of the manually operated lever, and means engaged by the lower end of said manually operated lever for releasing the stop-motion lever to stop the machine.

In testimony whereof, I have signed my name to this specification.

EDWARD B. ALLEN.
